FIG. 1

FIG. 2

I came upon a boister wallowing in the grass, then found a path leading up the hill. It turned aside for the boulders, and also for an undersized railway truck lying there on its back with its wheels in the air. One was off. The thing looked as dead as the carcass of some animal. I came upon more pieces of decaying machinery, a stack of rusty rails.

To the left a clump of trees made a shady spot.
